UNITED STATES PATENT OFFICE.

CYRUS P. GIFFORD, OF ERIE, PENNSYLVANIA.

LANTERN-BURNER.

No. 872,928.

Specification of Letters Patent.

Patented Dec. 3, 1907.

Application filed May 3, 1907. Serial No. 371,705.

To all whom it may concern:

Be it known that I, CYRUS P. GIFFORD, a citizen of the United States, residing at Erie, in the county of Erie and State of Pennsylvania, have invented certain new and useful Improvements in Lantern-Burners; and I do hereby declare the following to be a full, clear, and exact description of the invention, such as will enable others skilled in the art 10 to which it appertains to make and use the same, reference being had to the accompanying drawings, and to the letters of reference marked thereon, forming part of this specification.

15 My invention relates to lantern burners, and has for its object the construction and combination of a burner extinguishing mechanism in such a manner that while the lantern may be subjected to sudden, violent 20 jars and may be swung around without operating the extinguishing mechanism, yet, in case the lantern is overturned, it instantly becomes operative to extinguish it.

The features of my invention are herein- 25 after fully set forth and described and illustrated in the accompanying drawings in which:

30 Figure 1 is a view partially in elevation and partially in section of the base of a lantern embodying my invention. Fig. 2 is a top or plan view of the same. Fig. 3 is a detail view of a portion of the mechanism. Fig. 4 is a view partially in elevation and partially in section of a modification thereof. 35 Fig. 5 is a top or plan view of the same.

In these drawings A is the base of a lantern, B B the upright parts of the frame, C the lantern globe, and C' the globe support, all of the usual and ordinary construction.

40 The burner has the ordinary wick-tube D, the wick raiser D' and frame D² D³ of the usual construction. The vent-tube is made of a loose plate d, adapted to slide up and down along the side of the wick-tube D, 45 and on the top D² of the frame, I pivot, in ears d' d', the arms e e of an extinguisher cap E, the arms e e embracing the edges of the wick-tube D, and to the back of the vent-tube plate d, I secure a cross-bar e' 50 which extends laterally under the arms e e so that the raising or lowering of the vent-tube plate d operates to raise or lower the extinguisher cap E, as illustrated in dotted lines in Fig. 1. At one side of the lower 55 part D² of the burner frame I pivot a lever

F provided on its longer arm with a weight F', and to the lower part of the vent-tube plate d I secure a cross-bar f, one end of which is looped around the lever F, so that the raising or lowering of the lever F operates to raise or lower the vent-tube plate d and the mechanism connected therewith. On the short arm of the lever F, I pivot a swinging pendant F², and on the side of the lower part of the frame directly under the pendant F², there is a projecting shelf ledge G with which the lower end of the pendant F² is adapted to nearly contact when the lantern is in a vertical position, but which pendant F² swings to one side of the ledge G when the lantern is tipped, so as to pass off of the ledge G, as illustrated by dotted lines in Fig. 1 and permit the lever F to operate. Around the bearing f' of the lever F there is a spring f² which operates on the lever F in opposition to the weight F'. 60 65 70 75

In Figs. 3 & 4 of the drawings I show a structure in which all of its parts are the same as hereinbefore described, except that in place of the swinging pendant on the arm 80 of the lever F, and the ledge or plate G on the burner-frame, I secure to the lever F a downwardly projecting point F³, and on the burner-frame I make a slotted shell G', the bottom of which is concaved so that the 85 lowest point therein is directly under the point F³, on the lever F, and in this shell G', I place a ball H which normally rests directly under the point F³, but which rolls to one side thereof whenever the lantern is tipped, 90 so as to allow the end of the lever F to pass downward and operate the mechanism hereinbefore described.

The operation of these mechanisms is as follows: So long as the lantern is in a perpendicular position the weight F' operating on the lever F overcomes the tendency of the spring f² to raise the lever F, but when the lantern is tipped to one side in any direction, the spring f² overcomes the weight and 95 raises the lever F and the extinguishing mechanism connected therewith, and extinguishes the flame, and but for the action of the pendant F², or the ball G', a sudden jar, or the swinging of the lantern sidewise, would 100 operate the mechanism to extinguish the flame, the pendant or ball mechanism, however, prevents this, but if the lantern be tipped over the pendant or ball instantly 105 moves to one side, as illustrated by dotted 110

lines in Figs. 1 & 3, and permits the operation of the mechanism to extinguish the flame.

Having thus described my invention so as to enable others to construct and utilize the same, what I claim as new and desire to secure by Letters-Patent is:

The combination in a lantern-burner, of a burner-frame, a wick-tube, a vertically movable vent-tube plate at one side of the wick-tube, a lever pivoted to the upper part of the frame, an extinguisher on the free end of said lever, a connection between said lever and vent-tube plate so they will operate in unison, a spring actuated lever pivoted in the

lower part of the frame, a weight on the longer end of said lever, means connecting said lever with the lower part of the vent-tube plate, and mechanism engaging the shorter end of the spring actuated lever for preventing its operation when the lantern is in a vertical position, substantially as set forth.

In testimony whereof I affix my signature in presence of two witnesses.

CYRUS P. GIFFORD.
